UNITED STATES PATENT OFFICE.

LEONARD B. BAIRD AND BASCUM H. HARPER, OF TOWNLEY, ALABAMA, ASSIGNEES OF
ONE-THIRD TO DAVID F. McCULLAR, OF TOWNLEY, ALABAMA.

DESIGN FOR A SPIKE-BAR.

52,052.

Specification for Design. Patented May 28, 1918.

Application filed December 17, 1914. Serial No. 877,819. Term of patent 14 years.

To all whom it may concern:

Be it known that we, LEONARD B. BAIRD and BASCUM H. HARPER, citizens of the United States, residing at Townley, in the county of Walker and State of Alabama, have invented a new, original, and ornamental Design for Spike-Bars, of which the following is a specification, reference being had to the accompanying drawing, forming part thereof.

Figure 1 is a perspective view of the spike bar, showing our new design, and

Fig. 2 is a rear perspective view of our new design.

We claim:

The ornamental design for a spike bar, as shown.

LEONARD B. BAIRD.
BASCUM H. HARPER.
